UNITED STATES PATENT OFFICE.

SAMUEL BOLOZKY, OF WEST NEW YORK, NEW JERSEY, AND SAMUEL PEARL, OF BROOKLYN, NEW YORK.

FAN INSTALLATION.

Application filed March 13, 1926. Serial No. 85,674.

Our present invention has to do with fans such as used in tailors' shops and other shops; and it contemplates the provision of a peculiar and advantageous fan installation constructed with a view to permitting of the fan being readily put into and out of use, and also constructed so that the fan can be expeditiously and easily positioned for use to the best advantage.

10 Other objects and practical advantages of the invention will be fully understood from the following description and claims when the same are read in connection with the drawings, accompanying and forming part of this specification, in which:

Figure 1 is a view, partly in elevation and partly in section, illustrating our improvement complete.

20 Figure 2 is an enlarged fragmentary section showing one of the joints of our improvements.

Figure 3 is an enlarged elevation taken from a view point at the right of Figure 1 and showing the means whereby the drive pulley of our improvement may be put into and out of engagement with a belt.

25 Figure 4 is a horizontal section on an enlarged scale, taken in the plane indicated by the line 4-4 of Figure 1, looking downwardly.

Similar numerals of reference designate corresponding parts in all of the views of the drawings.

30 We show at 1 in Figure 1 a table, and in accordance with our invention a plate 2 is fixed at 3 to the said table and extends beyond the edge of the table top, the said extended portion of the plate 2 being provided at 4 with a circular aperture and at 5 with a slot one wall of which is toothed as designated by 6.

35 A rigid upright tube 7 is arranged in the aperture 4 of the plate 2 and is appropriately connected to the said plate 2 so as to be supported thereby. We would have it understood in this connection that when deemed expedient frictional contact between the tube 7 and the plate 2 may be depended upon for the support of the tube 7 by the plate 2, the said relative arrangement of the tube 7 and the plate 2 being advantageous inasmuch as it is calculated to permit of endwise adjustment of the tube 7. As before indicated, however, it is within the

purview of our invention to connect the tube 55 7 to the plate 2 in any manner consonant with the purpose of our invention.

40 At 8 in Figure 1, we show a belt, and it will be understood that the flexible shaft 9 of our improvement is equipped at one end 60 with a pulley 10 designed to be placed in engagement with one stretch of the said belt 8 and also adapted to be moved out of engagement with said belt. The flexible shaft 9 is disposed in the tube 7 and is rotatable 65 about its axis in the manner common to flexible shafts. The lower portion of the flexible shaft 9 is carried through a curvilinear tube section 11, the upper end of which is bifurcated and is provided with 70 arms 12 and 13, the said arms 12 and 13 being pivotally connected at 14 to the lower portion of the tube 7, and the arm 13 being merged into a hand lever 15 which extends through and is movable in the slot 5 of the 75 plate 2, and is adapted to be placed removably in interdental spaces of the toothed portion 6 of the plate 2 with a view to adjustably positioning the tube section 11. A suitable housing section 16 of flexible character is secured at its ends in the tube section 11 and in the tube 7 and receives the 80 flexible shaft 9 and is adapted to lend itself to movements of the tube section 11. Mani- 85 festly through the medium of the hand lever 15 and the construction associated with the said hand lever 15, the pulley 10 may be placed against or removed from the stretch of the belt 8, and by engagement of the lever 15 with the toothed portion 6 of the 90 plate 2, the pulley 10 may be detachably secured in either of said positions.

95 The upper portion of the tube 7 is preferably, though not necessarily, equipped with a thread holder of appropriate type, designated by 17.

Extending from the tube 7 is a tube section 18 disposed laterally to the tube section 7, and extending from the said tube section 18 is another tube section 19 of curvilinear form by which is carried a fan guard 20*. This fan guard 20* per se may be of any construction compatible with the purpose of our invention, and we, therefore, do not deem it necessary to enter into a detailed description of the same. The flexible shaft 9 extends through the tube sections 18 and 19 and is equipped at its forward end with

a fan 21 of appropriate type adapted to be freely turned in the guard 20*. The tube section 19 is fixed to a tubular member 20, Figure 2, and the said tubular member 20 is arranged in and adapted to be turned about its axis in the tube section 18. It will also be noted that the tubular member 20 is provided with a circumferential groove 21 which receives the inner end of a screw 22 threaded in the wall of the tube section 18. Manifestly when the screw 22 is loosened, the tubular member 20 may be turned about its axis in the tube section 18 for the proper positioning of the tube section 19 and the fan guard and fan, and after the said parts are adjusted as desired, the tube section 19 may be adjustably fixed with respect to the tube section 18 by tightening of the screw 22. The adjacent portions of the tube 7 and 20 the tube section 18 are connected together at 30 in the same manner that the tube section 19 is connected to the tube section 18. Consequently it will be understood that the tube section 18 may be swung laterally and adjustably fixed on the tube section or tube 7 so as to contribute to the desired positioning of the fan 21 and its guard 20.

It will be apparent from the foregoing that notwithstanding the advantages ascribed to our novel installation, the installation is simple and inexpensive in construction, is well adapted to withstand the usage to which installations of corresponding character are ordinarily subjected, and is adapted to enable a workman to position the overhanging or overhead fan to the best advantage according to the conditions to be met.

We have entered into a detailed description of the best practical embodiment of our invention of which we are cognizant in order to impart a full, clear and exact understanding of the said embodiment. We do not desire, however, to be understood as limiting ourselves to the precise construction and arrangement of elements as disclosed, our invention being defined by our appended claims within the scope of which modifications in structure and in arrangement may be made without departure from our invention.

Having described our invention, what we claim and desire to secure by Letters Patent, is:—

1. In combination, a rotary driving ele-

ment, an appropriately supported swingable tube, a tube section having a bifurcated portion the arms of which are disposed at opposite sides of and are pivotally connected to the first-named tube, and also having one of said arms merged into a hand lever, said lever of flexible or resilient character, a flexible shaft extending through and rotatable in the tube and said section, a pulley on said shaft and adapted to be moved by movement of the swingable tube sections 65 into and out of engagement with the rotary driving element, and an appropriately supported element having a rack for cooperation with said resilient lever.

2. In combination, a rotary driving element, an appropriately supported tube, a swingable tube section having a bifurcated portion the arms of which are disposed at opposite sides of and are pivotally connected to the first-named tube, and also having one of said arms merged into a hand lever, said lever of resilient character, a flexible shaft extending through and rotatable in the tube and said section, a pulley on said shaft and adapted to be moved by movement of the swingable tube section into and out of engagement with the rotary driving element, and an appropriately supported element having a rack for cooperation with said resilient lever; the opening formed by the bifurcation of the tubular section being bridged by a flexible housing containing the flexible shaft and secured in the adjacent portions of the tube and tubular section.

3. In combination, a rotary driving element, a flexible shaft, an element on said shaft and adapted to be put into and out of engagement with said rotary driving element, a tube through which the flexible shaft extends, a swingable tubular section also receiving the flexible shaft and pivotally connected to said tube, an appropriately supported rack, and a lever fixed with respect to the tubular section and adjustable relative to said rack for the 100 adjustable fixing of the element on the flexible shaft in engagement with the rotary driving element and out of engagement with respect to the same.

In testimony whereof we affix our signatures.

SAMUEL BOLOZKY.
SAMUEL PEARL.
